DESIGN FOR A COMBINATION SAFETY RAZOR SHARPENER AND CASE

Eric Muelberger, Jr., San Francisco, Calif.

Application June 28, 1937, Serial No. 70,095

Term of patent 14 years

To all whom it may concern:

Be it known that I, Eric Muelberger, Jr., a citizen of the United States, residing at San Francisco, in the county of San Francisco and State of California, have invented a new, original, and ornamental Design for a Combination Safety Razor Sharpener and Case, of which the following is a specification, reference being had to the accompanying drawing, forming a part thereof.

Figure 1 is a perspective view of a combination safety razor sharpener and case showing my new design; and

I claim:

The ornamental design for a combination safety razor sharpener and case, as shown.
